(57) **CLAIM**

The ornamental design for a gecko shaped bottle opener, as shown.

DESCRIPTION

FIG. 1 is a plan view of the top and bottom sides, which are mirror images of each other, of my new design for a gecko shaped bottle opener.

FIG. 2 is a right side plan view of the bottle opener shown in FIG. 1.

FIG. 3 is a left side plan view of the bottle opener shown in FIG. 1.

FIG. 4 is a front side plan view of the bottle opener shown in FIG. 1.

FIG. 5 is a rear side plan view of the bottle opener shown in FIG. 1.

FIG. 6 is a top perspective view of the bottle opener shown in FIG. 1.

FIG. 7 is a plan view of the top and bottom sides, which are mirror images of each other, an alternate embodiment for a gecko shaped bottle opener shown in FIG. 1, the only difference being the ring hole is at the mouth.

FIG. 8 is a right side plan view of the bottle opener shown in FIG. 7.

FIG. 9 is a left side plan view of the bottle opener shown in FIG. 7.

FIG. 10 is a front side plan view of the bottle opener shown in FIG. 7.

FIG. 11 is a rear side plan view of the bottle opener shown in FIG. 7; and,

FIG. 12 is a top perspective view of the bottle opener shown in FIG. 7.
